CLAIM

The ornamental design for a paint roller handle, as shown and described.

DESCRIPTION

FIG. 1 is a perspective view of a paint roller handle, showing my design;

FIG. 2 is front elevation view;

FIG. 3 is a rear elevation view;

FIG. 4 is a left side elevation view;

FIG. 5 is top view;

FIG. 6 is a right side elevation view; and,

FIG. 7 is a bottom view.

The broken line showing of a roller is for illustrative purposes only and forms no part of the claimed design.

FIG. 1

FIG. 2

FIG. 5

FIG. 4

FIG. 3

FIG. 6

FIG. 7
